UNITED STATES PATENT OFFICE.

ROBERT A. REESE, OF MINNEAPOLIS, MINNESOTA.

SCREEN FASTENER.

Application filed March 2, 1922. Serial No. 540,625.

To all whom it may concern:

Be it known that I, ROBERT A. REESE, a citizen of the United States, residing at Minneapolis, in the county of Hennepin 5 and State of Minnesota, have invented certain new and useful Improvements in Screen Fasteners; and I do hereby declare the following to be a full, clear, and exact description of the invention, such as will enable others skilled in the art to which it 10 appertains to make and use the same.

My invention has for its object to provide an improved fastening device for detachably securing screens in working relation to window frames and sash, and is especially well adapted for use in connection with a pivoted or swinging window sash of the kind disclosed in the prior U. S. patent to Frank Reese, 1,343,933, of June 22, 1920; and, to 15 this end, my invention consists of the novel devices and combinations of devices hereinafter described and pointed out in the claims.

The invention is illustrated in the accompanying drawings, wherein like notations refer to like parts throughout the several views.

In said drawings,

Fig. 1 is a view in front elevation showing part of a window frame, part of a window sash assumed to be of the kind disclosed in said prior Patent 1,343,933, and a screen mounted by means of my improved fastener to protect the opening in the window frame, which would be otherwise unguarded when the sash is swung into its open position, some portions being broken away;

Fig. 2 is a horizontal cross section on the irregular line 2—2—2—2 of Fig. 1;

Fig. 3 is a perspective view showing one of my fastening clamps detached, this being my preferred form for fastening the sides of the screen to the window frame, as illustrated in Figs. 1 and 2;

Figs. 4 and 5 are partial horizontal sections in the same plane as Fig. 2, but illustrating a slightly modified form of clamp for fastening the sides of the screen to the window frame;

Fig. 6 is a perspective view of the form of clamp shown in Figs. 4 and 5 detached;

Fig. 7 is a vertical section on the line 7—7 of Fig. 1, showing the form of clamp which I preferably employ for securing the lower end of an upper screen to the central cross

piece or mullion of a window sash of the kind disclosed in said prior patent to Reese, 1,343,933; and

Fig. 8 is a perspective view of the form 60 of clamp shown in Fig. 7 detached.

Directing attention first to Figs. 1, 2, 4 and 5, the numerals 9 and 10 represent metallic elements making up the side walls of a metallic window frame or casing, when 65 secured together in proper relation to each other. The top and bottom cross pieces or caps and sills of the window frame are composed of metal and may be of any suitable structure for co-operation with the side 70 walls of the window frame. The element 9 is of channel form, with its back flange longer than its front flange, and its front flange slightly bent to afford outer faces slightly inclined in respect to each other; 75 and the element 10 is of angular form in cross section and is set with its main vertical flange abutting the back flange of the element 9, and the inner member of its cross flange or ribs abutting one of the inclined 80 outer surfaces of the face flange of the element 9, being inclined to the same slope. This relation of said parts 9 and 10 leaves three points of the angle bar 10 projecting outward beyond the face flange of the element 9, as clearly shown in Figs. 2, 4 and 5.

The numeral 11 represents a window sash with metallic frame, the pieces of which are shown as composed of angle bars and which sash may be assumed to be centrally pivoted to the frame in the same manner as the sash disclosed in said prior Patent 1,343,933. The side pieces of the sash frame 11 are adapted to work against and between the inner or profile face of the 95 frame element 9, with one of its cross flanges abutting the face flange of the element 9, when the sash is in its closed position, as shown in the drawings, this cross flange being inclined to the same slope as the 100 abutting surface of said element 9.

The numeral 12 represents a screen, of the structure disclosed in U. S. Patent 1,216,495, granted to the assignee of Frank Reese, February 20, 1917; in which particular form of screen the screen cloth is held between telescoping sections of a two-part or sectional frame having projecting marginal flanges.

The numerals 13 represent a pair of angular guide strips secured to the inner marginal side flanges of said two-part screen 12.

The numerals 14 and 15 represent, respectively, a channel bar and an angle bar rigidly secured together and co-operating to form a side guide and joint strip. The lateral flanges of the channel bar 14 project toward the sides of the window casing or frame. I then provide a suitable clamp, which, in all forms thereof, has two portions which stand in angular relation to the body 10 of the clamp and are adapted to be made to engage and clamp fast to two of the projecting portions of the angle bar 10 of the window frame and to have the side guides for the screen detachably secured thereto, for holding the side guides in proper working position, in respect to the window sash and the window frame. In my preferred form of clamp, its body portion 16 and its angular portions 16^a and 16^b are formed integral 20 with each other. The portion 16^a is of hook shape at its outer end, and the portion 16^b is provided with a set screw 17 screw-seated therein; and, when the clamp is in working position, its hook ended portion 16^a engages 25 with the side rib or flange of the angle bar 10 of the frame, and the set screw 17 engages behind the front or facing rib or flange of said angle bar 10, and, when turned in the right direction, becomes operative to 30 secure the needed clamping action between the engaged parts, as is obvious from Fig. 2 of the drawing. After the said clamp has been so applied to the angle bar 10 of the main frame, the side guides, made up of the 35 parts 14 and 15, fastened together as before stated, are placed in working position, and the laterally projecting flange of the angle plate 15 will then abut the outer face of the body portion 16 of the clamp and is then 40 secured thereto by a set screw 18. The side guides for the sash will then be securely held in their proper working position relative to the sash and the window frame, and the screen 12 can be moved up and down between the said side guides, if desired; and a 45 limited motion of this sort is not only desirable but necessary, when my improvement is applied to a window of the kind shown in said prior patent to Reese, 1,343,933. The 50 window shown in said prior patent is a centrally pivoted single window adapted to fill the entire opening of the window frame, when in its upright or vertical position parallel with the frame, but which assumes an angular position, when swung on its pivots into its open position. The window sash 11, shown in my drawings, is assumed to be of the pivoted kind illustrated in said prior patent, and its central cross rib or mullion 55 is of angular form in cross section, and I connect the lower end of the screen 12 thereto by the means shown in Fig. 7 of my drawing; and, to this end, I provide a joint plate, shown as made up of a sheet of metal 19 60 coiled upon itself into a roll bead 19^a at its 65

outer edge, which is secured to the bottom flange of the inner section of the two-part screen 12 by a set screw 20. The inner portion of the sheet 19 is bent upward at an angle to the body portion of the sheet, so as 70 to be adapted to be seated between the projecting portions of two of the flanges of the mullion. Said sheet 19 is provided with a hole 21, as best shown in Fig. 7. I then provide a clamp for connecting this joint plate 75 19 to the mullion of the window sash, which, from the broad point of view, is similar to the clamp, hitherto described as used for connecting the side guides to the window frame, but differs therefrom in some of its 80 details, as is obvious from the illustration thereof given in Figs 7 and 8. This mullion clamp, like the other, has a body portion 22 and two portions 22^a and 22^b, which stand in angular relation to the body portion 22. 85 The portion 22^a is hook-shaped at its outer end and is adapted to engage over the upper vertical flange of the mullion of the window sash, and the portion 22^b is adapted to be passed through the hole 21 in the joint 90 plate 19 and under reach the projecting horizontal flange of the mullion and be made to engage therewith by a set screw 23, working in a screw-threaded seat 24 in that portion of the clamp, all as is clearly shown in Fig. 95 7. When the parts are so connected, the roll or bead 19^a of the plate 19 will yield or afford a slight spring action between the screen 12 and the window sash, and, under the oscillation of the window sash 11, the 100 screen 12 will receive a limited up and down motion between its side guides within pre-determined limits, shown as fixed by stops 25 formed integral with the guide plates 14 and projecting into the spaces between the side flanges of the frame sections of the screen 12, as shown in Fig. 2, and which are adapted to come up against yoke-shaped corner strips 26, shown as applied to the upper corners of the screen 12 in Fig. 1 of the 105 drawings.

In Fig. 4 of the drawings, I show a modified form of side clamp, wherein the body portion of the clamp is split, or, otherwise stated, wherein the clamp is made up of two 115 separate sections, each having a body portion 27 carrying one of the clamping elements, which stand in angular relation to their respective body section, and both of these are shown as of hook shape and adapted to engage, one over the profile rib and the other over the face rib of the angle plate 10 of the window frame, and then a set screw 28 works through a flange of the angle plate 15^a of the side guides to connect the clamp 120 and the guides and secure the clamping action.

In Fig. 5 of the drawings, I show a structure wherein the parts are the same as in Fig. 4, with the exception that the element 130

10^a of the casing has rib flanges of slightly different shape in cross section, and the side frame of the sash 11^a is of a corresponding different shape in cross section. This, however, makes no difference whatsoever in the action of the clamps or other parts of my fastener.

In the instances illustrated, a joint strip is employed with the clamp. The side joint strips are of such shape relative to the screen that they prevent the lateral displacement thereof, and the mullion joint strip, shown in Fig. 7, takes hold of the lower end of the screen frame and extends 15 to the full width of the screen and the window sash, and thereby helps to support the screen in its proper working position. In each instance, the joint strip is detachably secured to the clamp and the clamp connects 20 the same to a fixed part of the window frame or casing.

The joint strips may come with the screen and be treated as a part of the screen; and they may, of course, take various forms. For example, when my fastening device is applied to support a screen relative to an ordinary window sash and window frame, wherein the sash is mounted for straight line vertical sliding motion, instead of a pivotal motion, the joint strips may be afforded by an ordinary rectangular skeleton frame in which the screen proper is mounted and the clamps be applied to connect this skeleton frame to the window casing. In other words, the joint strip element may be greatly modified, according to the kind or style of the window and the screen.

The practicability and utility of my improved fastening device has been demonstrated by the successful commercial usage thereof.

It must be obvious that it saves a large amount of time in the mounting and dismounting of screens, as compared with the old method where the joint strips were

screwed fast to the window casing. This is especially true where fireproof metallic casings and window sash and screens are employed.

What I claim is:—

1. The combination with a metallic window frame, of a side guide and joint strip extending longitudinally at the side thereof, and a clamp to which said strip is secured detachably engaging the side of the window frame to hold said strip in position. 55

2. The combination with a metallic window frame, of an outwardly facing channel member, an angle member rigidly secured thereto, both forming a combined side guide and joint strip extending parallel to the side of said frame, a clamp to which said angle member is secured detachably engaging the side of said frame. 60

3. The combination with a metallic window frame having angularly extending flanges, of a guide member and joint strip extending along the side thereof having an outwardly extending vertical flange, a triangular clamp to which said flange is secured 70 engaging said flanges of the frame, and a set screw carried by said clamp and engaging one of said flanges of the frame to tighten said clamp and hold the guide member and joint strip firmly in position. 75

4. The combination with a metallic window frame having flanges extending substantially at right angles, of a combined guide and joint strip extending along the side of said frame, a triangular open-sided 80 clamp having one arm formed as a hook engaging over one of said flanges, a set screw disposed in the other arm of said clamp and engaging the other flange of said frame to draw said clamp to tightened position, said guide and joint strip being secured to said clamp whereby the same is held rigidly in position. 85

In testimony whereof I affix my signature.

ROBERT A. REESE.
